UNITED STATES PATENT OFFICE.

CHARLES T. BLOOMER, OF NEWARK, NEW YORK.

EGG-BOX.

1,143,745.

Specification of Letters Patent. Patented June 22, 1915.

Application filed April 24, 1915. Serial No. 23,719.

To all whom it may concern:

Be it known that I, CHARLES T. BLOOMER, a citizen of the United States, residing at Newark, in the county of Wayne 5 and State of New York, have invented a new and useful Egg-Box, of which the following is a specification.

The present invention appertains to paper boxes or receptacles, and aims to provide a 10 paper blank of novel formation, and adapted especially for forming an egg box, whereby a series of blanks may be readily and economically cut from a continuous sheet or roll of stock, and at the same time, when 15 the blanks are folded to form the boxes, the boxes will be of desirable construction, and will be devoid of objectionable gaps or openings in their walls or in the upper edges of their bodies.

20 It is the object of the invention to provide a paper box blank of such formation, as to reduce to a minimum the amount of stock required, and to also reduce to a minimum the amount of waste. The blanks are 25 of such peculiar configuration that they interlock or interfit in a unique manner, so that the blanks may be cut readily from the continuous sheet or roll of stock. It is, however, also the object of the invention to 30 provide a blank which when folded to provide a box, will produce a thoroughly practical and efficient box, and one which is even desirable and advantageous over prevailing boxes of the same general character.

35 Since the blanks are interfitted in a unique manner, a large quantity of blanks may be cut from the sheet of stock, whereby the number of blanks which can be cut from a given length of stock will be the maximum, 40 without jeopardizing the efficiency of the boxes when the blanks are folded.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 50 within the scope of what is claimed, without departing from the spirit of the invention.

The invention is illustrated in the accompanying drawings, wherein:—

Figure 1 is a plan view of several of the 55 present blanks, illustrating how they interlock or interfit, so that they can be cut from a continuous sheet or roll of stock. Fig. 2 is a perspective view of an egg box folded from one of the blanks. Fig. 3 is 60 a perspective view of the box partially folded. Fig. 4 is a plan view of the box in folded position. Fig. 5 is an end view of the box.

The formation of the blank will first be 65 described, and the various portions will be designated, for convenience, by the names of the portions of the box which they subsequently form. The edges of certain portions of the blank, and other parts are also 70 described as if the blank were folded to form the box.

The blank, which may be constructed of paper or other suitable stock, comprises a rectangular bottom 1 having front and back 75 walls 2 and 3 at its opposite edges, respectively, and end walls 4 at its ends. The back wall 3 has a rectangular top or cover 5, and the front wall 2 has flaps 6 at its ends, while the back wall 3 is provided with flaps 80 7 at its ends. The top 5 has a flap 8 at its free edge, and a flap 9 at each end. The ends of the flap 8 are provided with short tabs 10 which are adapted to be secured to the adjacent ends of the flaps 9.

85 The various portions of the blank have peculiar characteristics, whereby the desired objects are carried out. Thus, the flaps 9 and end walls 4 are slightly narrower than the front and back walls, to thereby reduce 90 the space between the successive blanks, as illustrated in Fig. 1. The flap 8 is also narrower than the front and back walls to decrease the width of the sheet or strip from which the blanks are cut. The flaps 8 and 95 9 of the top 5 may be narrower than the walls of the body of the box since they slip into the body and fully serve to close the space between the top and walls of the body. The flaps 6 and 7 of the front and back 100 walls are tapered and have their upper edges flush with the upper edges of the front and back walls, whereby when the blank is folded, the upper edge portions of the flaps 6

and 7 will project above the end walls 4 to increase the height of the end walls to that of the front and back walls. The lower edges of the flaps 6 and 7 are inclined or cut 5 obliquely, as at 11 and 12, respectively, whereby the said edges of the flaps 6 and 7 converge toward the upper edges of said flaps. The free ends of the flaps 6 and 7 are blunt whereby the free ends of the flaps 10 6 and 7 are arranged to abut against one another, when the blank is folded, for closing the gaps between the respective flaps 6 and 7. The flaps 6 and 7 are relatively long, or are longer than the widths of the end 15 walls 4 and flaps 9, but notwithstanding this fact, the blanks are arranged to interlock or interfit with the edges of the end walls and flaps 9, abutting, as seen in Fig. 1.

In order that the box may be folded, the 20 front wall 2 is provided with diagonal scores or fold lines 13 extending upwardly from its lower corners, and the end walls 4 are provided with diagonal scores or fold lines 14 extending upwardly from their 25 lower rear corners. The flaps 9 of the top 5 are provided with diagonal or oblique scores or fold lines 15 extending from the free corners of the top 5.

The upper rear corner portions 16 of the 30 end walls 4 are adapted to be secured by means of an adhesive or by any other suitable means to the flaps 7 and the said corner portions 16 are provided with notches or recesses 17 for receiving the free ends of the 35 flaps 7 of the adjacent blanks as seen in Fig. 1. This allows the flaps 7 to project beyond the end walls 4 and flaps 9.

In forming the box from the blank, the 40 walls 2, 3 and 4 are folded upwardly, and the flaps 6 are properly secured to the end walls 4, while the corner portions 16 of the end walls 4 are properly secured to the flaps 7. The tabs 10 of the flap 8 are suitably secured to the adjacent ends of the flaps 9. 45 When the box is thus completed the flaps 6 and 7 project above the end walls 4 and abut against one another to finish the ends of the body properly and without the presence of 50 objectionable gaps or openings in the ends of the body, although in certain cases, if desired, the flaps 6 and 7 may be cut shorter, which would leave gaps or openings between said flaps. Ordinarily, this would not be necessary or desirable. The free portions 18 55 of the flaps 7 project beyond the fold lines 14, whereby when the body is erected, the portions 18 in overlapping and resting against the end walls 4 beyond the fold lines 14, will serve to brace the ends of the body 60 and limit the outward movement thereof. When the box is filled, such as by a filler and eggs disposed in the cells thereof, the top or cover 5 may be readily closed, by slipping the flaps 9 and 8 thereof within the

body of the box. When the box is empty, 65 or before it is filled, it may be compactly folded into a flat condition. Thus, the front wall 2 may be folded upon the bottom 1, the end walls 4 and flaps 6 folding upon the bottom 1 and front wall 2, and the back wall 3 folding upon the end walls 4 while the flaps 7 and corner portions 16 of the end walls 4 fold between the back wall 3 and the body portions of the end walls 4. The flaps 9 of the top 5 may be folded against 75 the top to enable the flap 8 to be folded against the top and flaps 9. The boxes may therefore be completed at the factory and be shipped in a compact condition, to be readily unfolded or erected by the user. 80

Particular attention is directed to the manner in which the blanks interfit, as illustrated in Fig. 1, whereby a minimum amount of stock is necessary with a minimum amount of waste, and furthermore the 85 blanks may be cut from a continuous sheet or strip of stock. Notwithstanding these facts, the blanks when folded to complete the boxes, will provide boxes of desirable and effective construction. The adjacent 90 blanks are reversed, as seen in Fig. 1, and the adjacent edges of the blanks will thus interfit in the manner illustrated. Due to the differences in the widths of the flaps 8 and front walls 2 of the blanks, the bottoms 95 1 and tops 5 will be offset slightly relative to one another, but even then, each blank will interfit at its opposite edges with the reversely disposed adjacent blanks of like formation. The flaps 9 and end walls 4 of each blank abut against the end walls 4 and flaps 9 of the adjacent blanks, respectively and the lower or oblique edges of the flaps 7 will abut against one another, while the notches or recesses 17 accommodate the free 100 ends of the said flaps 7. The flaps 8 and 9 may fit upon the outer side of the body, as well as on the inside thereof, as will be obvious.

Having thus described the invention, what 110 is claimed as new is:—

A blank box comprising a rectangular bottom having front and back walls at its edges and end walls at its ends, the back wall having a rectangular top, the free edge of the 115 top having a flap, the ends of the top each having a flap, the said front and back walls each having a flap at each end, the first mentioned flap having short tabs at its ends to be secured to the adjacent ends of the second mentioned flaps, the first and second mentioned flaps and end walls being slightly narrower than the front and back walls, the flaps of the front and back walls being tapered and having their upper edges flush 125 with the upper edges of the front and back walls, the flaps of the front and back walls being longer than the widths of the end

walls and second mentioned flaps and the upper rear corners of the end walls having notches, whereby the opposite edges of the blank are adapted to interfit with like blanks 5 in reversed position, as and for the purposes set forth.

In testimony that I claim the foregoing as

my own, I have hereto affixed my signature in the presence of two witnesses.

CHARLES T. BLOOMER.
